UNITED STATES PATENT OFFICE

FRED W. JUENGST AND OSCAR M. ANDERSON, OF NEW BRITAIN, CONNECTICUT, AS-
SIGNORS TO LANDERS, FRARY & CLARK, OF NEW BRITAIN, CONNECTICUT, A COR-
PORATION OF CONNECTICUT

DESIGN FOR AN ELECTRIC FRUIT JUICE EXTRACTOR

Application filed September 29, 1932. Serial No. 45,160. Term of patent 14 years.

To all whom it may concern:

Be it known that we, FRED W. JUENGST, a citizen of the United States, and OSCAR M. ANDERSON, a subject of the King of Sweden, both residents of New Britain, in the county of Hartford, State of Connecticut, have invented a new, original, and ornamental Design for an Electric Fruit Juice Extractor, of which the following is a specification, refer-

ence being had to the accompanying drawings forming part hereof.

Fig. 1 is a perspective view of our new design; and

Fig. 2 is a side elevation of the same.

We claim:

The ornamental design for an electric fruit juice extractor, as shown.

FRED W. JUENGST.
OSCAR M. ANDERSON.
